ABSTRACT

A rail support system includes a clamp side having a channel to engage around a post; an extension curved around the channel; a first bar engaged with the extension; a handle attached to the first bar; and a second bar attached to the first bar via a lateral connector; pivoting the handle causes the second bar to apply pressure to the second side of the channel; a cradle side having an arm attached to the channel and extending away therefrom; and a cradle support attached to and extending away from the arm, the cradle support being vertically adjustable relative to the channel; the cradle support is to receive a rail; the clamp side is to secure to the post while the cradle side is to engage with the rail such that the post and the rail are held in position for welding together.

RAIL SUPPORT SYSTEM AND METHOD OF USE

CROSS REFERENCE TO RELATED APPLICATIONS

This application is a continuation of U.S. application Ser. No. 17/735,731, filed on May 3, 2022, which is a continuation of U.S. application Ser. No. 16/741,919, filed on Jan. 14, 2020. Each of the aforementioned applications is incorporated herein by reference in its entirety.

BACKGROUND

1. Field of the Invention

The present invention relates generally to support systems, and more specifically to a rail support system that supports a rail positioned between two posts, thereby allowing for a user to easily secure the rail and posts together, such as by welding.

2. Description of Related Art

In many construction systems, a user must secure one or more rails between posts. For example, as shown in FIG. 1, two posts **103, 105** are provided with two rails **107, 109** secured therebetween, creating a rail and post system **101**. During conventional construction methods, the user will have to support the rail and weld or otherwise secure the rail at the same time, which is cumbersome and difficult.

Accordingly, it is an object of the present invention to provide for a support system that easily allows for a user to secure the rail between the two posts, thereby freeing up the user's hands for welding the two together.

DESCRIPTION OF THE DRAWINGS

The novel features believed characteristic of the embodiments of the present application are set forth in the appended claims. However, the embodiments themselves, as well as a preferred mode of use, and further objectives and advantages thereof, will best be understood by reference to the following detailed description when read in conjunction with the accompanying drawings, wherein:

FIG. 1 is a front view of a conventional rail and post system;

FIG. 2 is an isometric view of a support system in accordance with the present application;

FIG. 3 is an isometric view of the system of FIG. 2 with a rail supported therein;

FIG. 4 is a front view of the system of FIG. 2 with the channel separated;

FIG. 5 is a flowchart of a method of use of the system of FIG. 2;

FIG. 6A is a side view of an extension in accordance with an alternative embodiment of the present application; and

FIG. 6B is a side view of an alternative embodiment of the clamp in accordance with the present application.

While the system and method of use of the present application is susceptible to various modifications and alternative forms, specific embodiments thereof have been shown by way of example in the drawings and are herein described in detail. It should be understood, however, that the description herein of specific embodiments is not intended to limit the invention to the particular embodiment disclosed, but on the contrary, the intention is to cover all

2

modifications, equivalents, and alternatives falling within the spirit and scope of the present application as defined by the appended claims.

5 DETAILED DESCRIPTION OF THE PREFERRED EMBODIMENT

Illustrative embodiments of the system and method of use of the present application are provided below. It will of course be appreciated that in the development of any actual embodiment, numerous implementation-specific decisions will be made to achieve the developer's specific goals, such as compliance with system-related and business-related constraints, which will vary from one implementation to another. Moreover, it will be appreciated that such a development effort might be complex and time-consuming, but would nevertheless be a routine undertaking for those of ordinary skill in the art having the benefit of this disclosure.

10 The system and method of use in accordance with the present application overcomes one or more of the above-discussed problems commonly associated with conventional rail and post systems. Specifically, the present invention provides for a rail support system that includes a clamp and a cradle, thereby allowing for the user to easily secure the system to a post and support a rail such that a user has free hands to secure the rail and post together. These and other unique features of the system and method of use are discussed below and illustrated in the accompanying drawings.

15 The system and method of use will be understood, both as to its structure and operation, from the accompanying drawings, taken in conjunction with the accompanying description. Several embodiments of the system are presented herein. It should be understood that various components, parts, and features of the different embodiments may be combined together and/or interchanged with one another, all of which are within the scope of the present application, even though not all variations and particular embodiments are shown in the drawings. It should also be understood that the mixing and matching of features, elements, and/or functions between various embodiments is expressly contemplated herein so that one of ordinary skill in the art would appreciate from this disclosure that the features, elements, and/or functions of one embodiment may be incorporated into another embodiment as appropriate, unless described otherwise.

20 The preferred embodiment herein described is not intended to be exhaustive or to limit the invention to the precise form disclosed. It is chosen and described to explain the principles of the invention and its application and practical use to enable others skilled in the art to follow its teachings.

25 Referring now to the drawings, FIG. 1 depicts a support system **201** in accordance with a preferred embodiment of the present application. System **201** overcomes one or more of the above discussed problems.

30 System **201** includes a clamp side **205** having a channel **209** with a first side **213** and a second side **211**, the first side and second side are configured to engage around a post **207**, thereby securing to the post. It should be appreciated that the channel can vary in diameter or the like. As shown, system **201** further includes an extension **215** extending away from the second side **211**. The extension will extend around the channel as shown and engage with a plate **217** that has a tightening screw **221** extending therethrough and engaged with a brace **219** against the first side **213**.

It should be appreciated that the use will rotate the tightening screw 221 to pull the channel together around the post 209. This allows for the user to secure the channel to a post at a desired location.

System 201 further includes a cradle side 203 having an arm 223 attached to the channel and extending away therefrom. It should be appreciated that the arm 223 can extend away at various angles as needed or desired based on manufacturing or functional considerations. A cradle support 225 attached to and extending away from the arm 223 via a second tightening screw 227. It should be appreciated that this second tightening screw provides for adjustment to the cradle support 225.

In FIG. 3, the support system 201 is shown engaged with a rail 303 and a post 305. As shown, the rail 303 is held in a desired position 301 relative to post 305. The user then has free hands to secure the rail and post together.

In FIG. 4, the system 201 is shown with the first side 213 and the second side 211 disengaged. As shown, the sides come apart, which allows for a user to secure the system to a post at a desired location easily. Also shown in FIG. 4 is a stabilizing rod 402 that provides for preventing rotation of the clamping surface and an attachment 404 for attaching a ground clamp as needed.

In FIG. 5, a flowchart 501 depicts the method of use of system 201. During use, the user will secure the clamp side to a first post, as shown with box 503. The user will then adjust the cradle side as necessary to the correct position, as shown with box 505. The user can then proceed to place a rail within the cradle support and secure the rail and post together, such as through welding, as shown with boxes 507, 509.

In FIG. 6A, a side view depicts an alternative embodiment of an extension 601 to replace extension 215 in some embodiments. Extension 601 is configured to operate substantially similar to extension 215. As shown, this embodiment includes an attachment 404 to attaching a ground clamp as needed, and further includes an L shaped cutout 603. As shown in a side view in FIG. 6B, wherein a clamp side 605 of an alternative embodiment is shown. In this embodiment, extension 215 is configured to engage with a first bar 607 of a lever style clamp 609, the lever style clamp 609 having the first bar 607 pivotally engaged with a handle 611 such that when the handle pivots, as shown with arrow B, pressure is applied to a side 613 that further presses against a post 615 as shown with arrow A. The first bar 607 is attached to a second bar 608 via a lateral connector 610. It should be appreciated that this embodiment can include some or all of the other features discussed above.

The particular embodiments disclosed above are illustrative only, as the embodiments may be modified and practiced in different but equivalent manners apparent to those skilled in the art having the benefit of the teachings herein. It is therefore evident that the particular embodiments disclosed above may be altered or modified, and all such variations are considered within the scope and spirit of the application. Accordingly, the protection sought herein is as set forth in the description. Although the present embodiments are shown above, they are not limited to just these embodiments, but are amenable to various changes and modifications without departing from the spirit thereof.

What is claimed is:

1. A rail support system, comprising:
a clamp side having:

a channel molded a first side and a second side, the first side and second side configured to engage around a post;
an extension having:

a curved section curved around the second side of the channel;

first end and a second end extending away from the second side;

a first bar engaged thereto such that the channel is positioned between the curved section and the first bar;

a handle pivotally attached to the first bar; and
a second bar attached to the first bar via a lateral connector;

wherein pivoting the handle causes the second bar to apply pressure to the second side of the channel;

a cradle side having:
an arm attached to the channel and extending away therefrom; and

a cradle support attached to and extending away from the arm, the cradle support being vertically adjustable relative to the channel;

wherein the cradle support is configured to receive a rail;

wherein the clamp side is configured to secure to the post while the cradle side is configured to engage with the rail such that the post and the rail are held in position for welding together.

2. A method of holding a first post and a rail in place for welding, the method comprising:

providing the system of claim 1;

adjusting the cradle side;

placing the rail within the cradle; and

welding the rail and the first post together.
